FIG. 2

FIG. 4

FIG. 1

FIG. 5

FIG. 3

FIG. 6

FIG. 9

FIG. 7

FIG. 10

FIG. 8

FIG. 1 is a front view of one embodiment of a photographic camera showing my new design with the flash holder retracted into the camera body, said camera in this embodiment having a reciprocal film advancing lever extending from one end of the camera body adjacent the top thereof,

FIG. 2 is a top plan view thereof,

FIG. 3 is a rear view thereof,

FIGS. 4 and 5 are elevational views of opposite ends thereof,

FIG. 6 is a bottom view thereof,

FIGS. 7-10 correspond to FIGS. 1, 3, 4 and 5, respectively, but show the flash holder in an extended or operative position,

FIGS. 11-16 show the same camera in the same positions as shown in FIGS. 1-6, but modified by replacing the film advancing lever extending from one end of the camera by a cylindrical winding knob or spring motor housing situated atop the camera adjacent one end thereof.

The generic design of the camera is the same in all instances in that it consists of a generally rectangular camera body having front and back sections, all four bounding surfaces of which taper or converge toward one another and into vertical front and back surfaces which are relatively smaller in all outside dimensions than the intermediate portion of the camera body. In addition, the ornamentation of all corresponding surfaces of the two embodiments are alike.

The broken-line showing of a flash lamp in FIG. 7 is for illustrative purposes only.

I claim:

The ornamental design for a photographic camera, as shown and described.
